COMBINED BOTTLE CLOSURE AND LIQUID DISPENSER

Clifford R. Jennings, 148 Lincoln St., Hingham, Mass.

Filed Sept. 8, 1961, Ser. No. 66,648

Term of patent 14 years

(Cl. D58—26)

FIG. 1 is a side elevational view of a combined bottle closure and liquid dispenser, embodying my new design; the opposite side being a mirror image thereof;

FIG. 2 is a rear elevational view thereof;

FIG. 3 is a front elevational view thereof; and

FIG. 4 is a top plan view thereof.

I claim:

The ornamental design for a combined bottle closure and liquid dispenser, substantially as shown and described.
